UNITED STATES PATENT OFFICE.

WILLIAM A. JAMES, OF GALENA, ILLINOIS, ASSIGNOR OF TWO-THIRDS TO
JESSE G. CROOKS AND CHRISTOPHER HERON, OF SAME PLACE.

CARPENTER'S GAGE.

SPECIFICATION forming part of Letters Patent No. 242,096, dated May 24, 1881.

Application filed March 12, 1881. (Model.)

To all whom it may concern:

Be it known that I, WILLIAM A. JAMES, of Galena, in the county of Jo Daviess, and in the State of Illinois, have invented certain new and useful Improvements in Carpenters' Gages; and I do hereby declare that the following is a full, clear, and exact description thereof, reference being had to the accompanying drawings, and to the letters of reference marked thereon, making a part of this specification.

This invention relates to certain improvements in carpenters' gages, and which is equally applicable to the ordinary gage or to mortise-gages.

The invention has for its objects to provide a means whereby the bar of the gage may be more readily and conveniently traversed along the surface of the timber, as more fully herein-after specified. These objects I attain by the mechanism illustrated in the accompanying drawings, in which—

Figure 1 represents a bottom view of my improved gage. Fig. 2 indicates a transverse section of the gage on the line $x x$ of Fig. 1, and Fig. 3 a view of the forward end of the gage-bar.

The letter A indicates the bar of the gage, which is rectangular in cross-section, as usual.

The letter B indicates the slide, which is constructed in the ordinary manner and fitted upon the bar in such a way that it may be readily moved back and forth upon the same. The said slide is provided with the usual set-screw, C, by means of which it may be clamped in any desired position. The lower side of the

bar is provided with one or more longitudinal grooves, D, semi-cylindrical in cross-section.

The letter E indicates a roller, one being provided for each groove, and extending longitudinally through the same, being journaled at opposite ends in bearings in the plates F G. The forward plate has a vertical aperture, H, through which is passed the forward marker, I, which is adjustable in said aperture.

In the present instance the apparatus is represented as a mortise-gage, and is provided with two rollers. Between the rollers is formed a longitudinal groove, K, in which is adapted to slide a bar, L, which carries at its forward end a marker, M. The said bar, at its rear, end is provided with a button or projection, N, by which it may be adjusted in its groove.

The operation of my improved gage will be readily understood, in connection with the above description, without further explanation.

Having thus described my invention, what I claim, and desire to secure by Letters Patent, is—

In combination with the bar A, provided with rollers, as described, the adjustable marker I, 60 sliding marker M, secured to bar N, and the slide B, all arranged substantially as specified.

In testimony that I claim the foregoing I have hereunto set my hand this 2d day of March, 1881.

WILLIAM A. JAMES.
